UNITED STATES PATENT OFFICE.

LARS HUGO BERGMAN, OF CHICAGO, ILLINOIS.

PULVERIZED-FUEL FURNACE.

1,421,898.

Specification of Letters Patent. Patented July 4, 1922.

Application filed January 7, 1920. Serial No. 350,015.

To all whom it may concern:

Be it known that I, LARS HUGO BERGMAN, a citizen of the United States, and a resident of the city of Chicago, in the county of Cook 5 and State of Illinois, have invented certain new and useful Improvements in a Pulverized-Fuel Furnace; and I do hereby declare that the following is a full, clear, and exact description of the same, reference being had 10 to the accompanying drawings, and to the numerals of reference marked thereon, which form a part of this specification.

This invention relates to pulverized fuel furnaces, more particularly those in which 15 separate streams of air are introduced therein, one to propel the fuel into the furnace, and the other to supply the necessary additional oxygen for complete combustion.

Powdered fuel, even when crushed so that 20 80% will pass 100 mesh, takes an appreciable time to burn so that provision must be made to allow sufficient time for complete combustion.

Not only is it necessary to allow time for 25 combustion, but it is also desirable to provide means for intimately mixing the powdered fuel with the air in which it is burnt.

One of the objects, therefore, of the present invention is to provide means whereby 30 the powdered fuel and air are caused to travel over a path of sufficient length to allow of complete combustion of the fuel.

Another object of the invention is to provide means for intimately mixing the powdered fuel with the air in which it is burnt. 35

A further object of the invention is to provide improved means for collecting the ash produced by the burning of the fuel.

Other and further important objects of 40 the invention will be apparent from the disclosures in the drawings and specification.

The invention (in a preferred form) is illustrated in the drawings and hereinafter more fully described.

45 On the drawings:

Figure 1 is a front elevation of a furnace and boiler constructed in accordance with the present invention, one-half of the figure being in section on the line 1—1 of Figure 2.

50 Figure 2 is a section on the line 2—2 of Figure 1.

Figure 3 is a section on the line 3—3 of Figure 2, the nozzles being shown in elevation.

55 Figure 4 is a vertical section through one of the pulverized fuel injectors.

As shown on the drawings:—

The furnaces shown form the fire-boxes of a series of water-tube boilers, each denoted by the reference numeral 1, mounted in brick 60 work 2 in the usual way. The furnace itself consists of a fire-brick chamber 3 having an arched roof 4, a front wall 5, and a bottom 6, the rearward part 7 of which slopes upwardly towards the water tubes 8 of the 65 boilers. Powdered fuel, usually coal dust, is stored in a series of hoppers 9 arranged along the front of the boilers. The lower parts of these hoppers communicate with worm feeding devices 10 adapted to supply 70 powdered fuel at a uniform rate to vertical pipes 11 which carry the fuel to fuel nozzles 12. The necessary air for injection of the powdered fuel and for the combustion thereof is supplied from a blower or fan (not 75 shown) through a conduit 13 from which lead branch connections 14 to the respective fuel nozzles.

The construction of each nozzle is shown more particularly in Figure 4 in which it is 80 seen that the nozzle comprises a chamber 15 at its upper end to which air is supplied through one of the pipes 14. From the lower end of this chamber extend curved concentrically arranged pipes 16 and 17. Centrally arranged in the top of the chamber 15 is the end of the pipe 11 to which is connected by suitable means a conical jet 18, by which powdered fuel is directed into the inner of the two concentric pipes. The air 90 flowing from the chamber 15 downwardly through the pipes 16 and 17 is divided into two concentric streams, the outer one being of air only while the inner one consists of air carrying with it particles of coal dust. 95 It will be seen that slow moving currents of air will be sufficient to carry the fuel into the furnace, on account of the peculiar construction and disposition of the burners.

These nozzles are arranged in the side 100 walls 21 of the chamber 3 adjacent to its upper edge so as to direct streams of air inwardly, downwardly and forwardly as indicated by the arrows in the various figures. Adjacent each nozzle the side walls are 105 thickened, as at 22, so that the entire nozzle is surrounded by firebrick and thereby protected against the extreme heat of the furnace. Pairs of nozzles are employed to produce converging and mutually impinging 110 streams of air with the result that each of the streams is thoroughly broken up, thereby

intimately mixing the air introduced merely for the purpose of completing combustion with the streams of air which act to propel the pulverized coal into the furnace. In this way a very satisfactory intermixture of the fuel and the air is obtained. Further, by directing the streams of air downwardly and forwardly the particles of fuel are retained in the chamber 3 sufficiently long either to burn completely therein or to burn to such an extent that combustion is completed as the gases pass through the tubes 8 of the boilers. One other result of causing the gases to flow around this circuitous and roughly circular path is to aid in the separation of the ash which is thrown against and collects upon the inclined bottom 7 of the chamber. The ashes may be removed from time to time through doors 20 arranged along the lower edge of the front wall 5. Sight holes 19 may also be provided in this front wall so that the operation of the furnace may be observed.

I am aware that many changes may be made and numerous details of constructions may be varied through a wide range without departing from the principles of this invention, and I therefore do not purpose limiting the patent granted hereon otherwise than necessitated by the prior art.

I claim as my invention:

1. In a furnace for pulverized fuel, a combustion chamber, downwardly directed fuel conduits, air chambers one surrounding the mouth of each fuel conduit, mixture conduits leading from each of said air chambers into the combustion chamber, said mixture con-

duits being curved so as to deliver streams inclined downwardly and toward the front of the combustion chamber, said inclined streams converging toward the front of the combustion chamber, an outlet at the rear of said combustion chamber, means for conveying pulverized fuel to said fuel conduits, and means for conveying air under pressure to said air chambers.

2. In a furnace for pulverized fuel, a combustion chamber, downwardly directed fuel conduits, air chambers one surrounding the mouth of each fuel conduit, mixture conduits leading from each of said air chambers into the combustion chamber, said mixture conduits being curved so as to deliver streams inclined downward and toward the front of the combustion chamber, said inclined streams converging toward the front of the combustion chamber, air conduits surrounding each of said mixture conduits respectively, whereby the streams delivered each consist, at the point of delivery, of a central stream of mixture of air and fuel and an annular surrounding stream of air relatively free from fuel, an outlet at the rear of said combustion chamber, means for conveying pulverized fuel to said fuel conduits, and means for conveying air under pressure to said air chambers.

In testimony whereof I have hereunto subscribed my name in the presence of two subscribing witnesses.

LARS HUGO BERGMAN.
